UNITED STATES PATENT OFFICE.

GEORGE E. RANDLES, OF CLEVELAND, OHIO, ASSIGNOR, BY MESNE ASSIGNMENTS, TO
THE FOOTE-BURT COMPANY, A CORPORATION OF OHIO.

WRINGER.

1,411,743.

Specification of Letters Patent.

Patented Apr. 4, 1922.

Application filed May 19, 1920. Serial No. 382,540.

To all whom it may concern:

Be it known that I, GEORGE E. RANDLES, a citizen of the United States, residing at Cleveland, in the county of Cuyahoga, State 5 of Ohio, have invented certain new and useful Improvements in Wringers, of which the following is a specification.

The present invention relates to clothes wringers and more particularly to power driven clothes wringers such as are used with power washing machines. In connection with the use of such wringers there is danger that the operator may accidentally get a finger or hand between the rolls and in 15 such case it is desirable to quickly release the spring pressure on the rolls. Also it may sometimes be desirable to be able to quickly release the rolls in case clothes or other articles being wrung get wound around 20 the rolls. For this purpose there are in use what are termed quick release mechanisms for wringers and the object of my present invention is to provide an improved structure and arrangement in a mechanism of 25 this character.

For a consideration of what I believe to be novel and my invention, attention is directed to the accompanying description and the claims appended thereto.

30 In the drawing, Fig. 1 is a side elevation of the upper part of a wringer embodying my invention, the wringer frame being broken away for purposes of illustration; Fig. 2 is a section taken on line 2—2, Fig. 1; 35 Fig. 3 is a section similar to Fig. 1, but showing the parts in released position; Fig. 4 is a side elevation of a complete wringer; Fig. 5 is a view similar to Fig. 1 of a modified form of my invention; Fig. 6 is a section 40 taken on line 6—6, Fig. 5; Fig. 7 is a view similar to Fig. 6 showing the parts in released position, and Fig. 8 is a section taken on line 8—8, Fig. 5.

Referring to Sheet 1 of the drawings, 45 indicates the frame of a wringer, 11 the rolls, and 12 a gear box in which is a gearing shifted by handle 13 for starting, stopping and reversing the rolls. The wringer is shown as being mounted on a post 14 so that it can swing in a horizontal plane. The ends of the rolls have stub shafts, which are carried in suitable bearings in the sides of the frame as is well understood and extending across the frame is a flat spring bar 55 15, the ends of which rest on the upper

wringer bearings for forcing the rolls together. Connected to the center of bar 15 by means of a swivel connection 16 is a threaded post 17 having an operating handle 18 on its upper end. As is well understood, 60 when post 17 is screwed down spring bar 15 will force rolls 11 together while when it is screwed up it will relieve the tension on the rolls.

Now, according to my invention I provide 65 a two part or split nut in which post 17 screws and arrange my mechanism so that the two parts of the nut are normally held together in engagement with post 17 but may be instantly moved apart to release 70 post 17, thereby releasing spring bar 15 and hence the pressure on rolls 11. The arrangement is also such that the parts of the nut may be released instantly from either side of the wringer, the releasing handle being 75 arranged in the most convenient positions for the operator.

The split nut is arranged directly beneath the top wall of the wringer frame and comprises two parts, 20 and 21. Part 20 is carried on one end of an arm 22, the other end of which is pivoted by a pivot pin 40 to the end of an arm 23 which in turn is pivoted on a fixed shaft 24 depending from the top of the wringer frame. Arms 22 and 23 form a toggle which when straight as shown in Figs. 1 and 2 holds nut part 20 in engagement with the threads on post 17. When the toggle is broken, as shown in Fig. 3 nut part 20 is moved out of engagement 90 with the threads of post 17. Nut part 21 is carried in a similar manner on the end of an arm 25 pivoted by a pivot pin 41 to a second arm 26 which in turn is pivoted on a fixed shaft 27, arms 25 and 26 forming a 95 toggle for nut part 21 which operates in the same manner as does the toggle for nut part 20. The two toggles are operated by a lever arrangement which in Figs. 1, 2 and 3 comprises two arms 28 and 29 formed integral with or as continuations of toggle arm 25. Arm 28 passes beneath nut parts 20 and 21 and has an enlarged slot 30 through which post 17 passes. At an intermediate point arm 28 is connected to the toggle comprising arms 22 and 23 by means of pivot pin 40 which projects down through an elongated slot 31 in arm 28. On the free end of arm 28 is a post 32 which projects through one side wall of the wringer frame and has 110

2
a knob 33 on its end. Arm 29 passes beneath shaft 27 and has a post 34 on its end which projects out through the other side wall of the wringer frame and has a knob 35 on its end. At 36 are pads which form stops for the toggles.

When the toggles are straight as shown in Figs. 1 and 2, the parts 20 and 21 of the nut are held in engagement with the threads on post 17 and the post can be screwed up and down through the nut at will to decrease or increase the spring tension on rolls 11. The toggles when straight as shown in Figs. 1 and 2, are arranged preferably to move slightly beyond dead center so they lock in set position as is well understood. If at any time it is desired to instantly release the tension on the rolls, all that is necessary is to push inward on either knob 33 or knob 35 when both toggles will be broken as shown in Fig. 3 and the two parts of the nut moved out of engagement with the threads on post 17. This, of course, releases spring bar 15 and permits the rolls 11 to spring apart. In Fig. 3 nut part 20 and a part of arm 22 are broken away to better illustrate the parts beneath them. When either knob 33 or 35 is pushed to break the toggles, arms 28, 25 and 29 act in substance as a continuous lever which pivots around post 17, an anti-clockwise movement of such lever as shown in Figs. 2 and 3 being required to open the toggles. To bring the parts of the nut back into engagement with the threads on post 17 and reset the toggles all that is necessary is to pull out on either knob 33 or 35 as is obvious.

On Sheet 2 of the drawing I have shown a modified arrangement of my invention wherein the operating lever for breaking and resetting the toggles which carry the parts of the nut is formed as an entirely separate lever connected by pins to the toggles.

Referring to Sheet 2 whereon parts corresponding to those of Sheet 1 are indicated by the same reference numerals with the exponent "a" added, 15^a indicates the bar spring for the wringer rolls, 17^a the threaded post, and 16^a the swivel connection between them. 20^a and 21^a are the two parts of the nut, arms 22^a and 23^a forming the toggle for nut part 20^a and arms 25^a and 26^a forming the toggle for nut part 21^a. 24^a and 27^a are the pivot shafts for arms 23^a and 26^a. For breaking and resetting the toggles I provide a lever 45 which turns about post 17^a being provided with an oversized opening 46 at its center through which post 17^a passes. In turning, lever 45 pivots on the pads on the inner surfaces of the wringer frame as best shown in Fig. 8. The ends of lever 45 are curved outwardly in opposite directions, such ends projecting through openings in the side walls of the wringer frame and terminating in knobs 47 and 48. On the under sides of toggle arms 22^a and 25^a are pads 49

and 50 against which flat surfaces on lever 45 rest and at which points lever 45 is pivotally connected to such toggle arms by pins 51 and 52, there being elongated slots 53 and 54 in toggle arms 22^a and 25^a through which pins 51 and 52 pass. Pins 51 and 52 have heads which engage the top of arms 22^a and 25^a along the edges of the slots. Extending across the wringer frame beneath toggle arms 22^a and 25^a are pins 55 and 56 which form supports and guide members for such arms. Stop pads 57 are provided for limiting the movements of the toggles in either direction. Lever 45 is provided with a pad 58 having a finished surface which rests against the bottom of nut parts 20^a and 21^a.

When lever 45 is in the position shown in Figs. 5 and 6, the two toggles are straightened out and the parts 20^a and 21^a of the nut are held in engagement with the threads on post 17^a permitting the post to be screwed down and up at will to increase and decrease the tension between rolls 11. When it is desired to quickly relieve the tension on rolls 11 this may be done by pushing in on either knob 47 or 48 to turn lever 45 and thereby break both toggles, moving the parts of the nut out of engagement with the threads on post 17^a as shown in Fig. 7. The wringer rolls can then immediately spring apart.

As will be clear, a quick release mechanism made in accordance with my invention is simple in structure, requiring but few parts none of which must be accurately dimensioned or fitted which makes for low cost in manufacturing and ease in assembling. At the same time, the arrangement is positive in operation and not likely to get out of order. This latter is of prime importance for while the quick release mechanism may be called upon to operate but seldom, when it is called upon the operation wants to be sure and positive. To break the toggle requires but a small amount of pressure applied to either of the knobs so that the release of the wringer rolls may be accomplished almost instantly. It is also advantageous to have the toggles broken by a push on the lever as this does not require taking hold of the operating knobs but merely pushing on them, a thing which can be done in the shortest space of time; and by having a knob on each side of the wringer there is always one directly adjacent the operator whether wringing clothes from one side of the wringer or the other.

In both forms of the invention, the post 17 or 17^a passes freely through the opening in the top of the wringer frame and the nut parts 20 and 21 or 20^a and 21^a rest against the under side of the top of the wringer frame. The wringer frame thus takes the upward thrust of post 17 or 17^a on the nut parts. The opening in the wringer frame through which post 17 or 17^a passes is pro-

vided with a flange around it and this forms a guide for such post so that when it is released from between the nut parts it is held vertical and guided in its movements. This 5 is important in the quick release of the wringer as it keeps the post from moving sideways with either nut part thus insuring that both halves of the nut are quickly and simultaneously moved from engagement 10 with the threads on the post. The threads on the posts and nut parts are preferably of suitable V-shape of such an angle that the upward pressure of the posts tends to spread the nut parts. In either modification when 15 the operating lever turns it pivots about post 17 or 17^a as an axis; in turning, however, it is held by and turns on the pads on the inner side walls of the frame.

In accordance with the provisions of the 20 patent statutes, I have described the principles of operation of my invention, together with the apparatus which I now consider to represent the best embodiment thereof, but I desire to have it understood that the apparatus shown is only illustrative and that the 25 invention may be carried out by other means.

What I claim as new and desire to secure by Letters Patent of the United States is:

1. In a wringer, the combination of a 30 frame, rolls carried therein, a threaded post for increasing and decreasing the tension on said rolls, said post passing upward through an opening in the top wall of the frame and being guided thereby, a nut for the post comprising a plurality of parts, arms pivoted on the frame beneath its top wall which carry said nut parts, means for holding said nut parts in engagement with said post, and means for releasing said holding means 40 whereby said nut parts may simultaneously move away from said post.

2. In a wringer, the combination of a frame, rolls carried therein, a threaded post for increasing and decreasing the tension on 45 said rolls, said post passing upward through an opening in the top wall of the frame and being guided thereby, a nut for the post comprising a plurality of parts, arms pivoted on the frame beneath its top 50 wall which carry said nut parts, means for holding said nut parts in engagement with said post, and means projecting through opposite sides of the frame for releasing said holding means and effecting the simultaneous 55 movement of said nut parts away from said post.

3. In a wringer, the combination of a frame, rolls, a threaded post which projects through an opening in the frame and is 60 adapted to increase and decrease the tension on the rolls, a two part nut located within the frame, a carrying member for each nut part, said carrying members being pivotally mounted in the frame, means for holding 65 said carrying members in positions where the

nut parts are in engagement with the threads on said post, and means for releasing said holding means to effect the simultaneous movement of the nut parts away from the post.

4. In a wringer, the combination of a frame, rolls carried therein, a threaded post for increasing and decreasing the tension on said rolls, said post passing upward through an opening in the top wall of the frame and 70 being guided thereby, a nut for the post comprising two parts, said parts being located within the frame beneath the top wall thereof, arms within the frame to which said nut parts are connected, and means projecting beyond the frame for positively and simultaneously moving both said nut parts into and out of engagement with the threads on said post.

5. In a wringer, a frame, rolls, a threaded 80 post for increasing and decreasing the tension on the rolls, a split nut which normally engages the threads on said post, toggle means connected to the parts of the nut, and means projecting beyond the frame of the 90 wringer for breaking said toggle means.

6. In a wringer, having a frame, rolls, and spring means for yieldingly holding the rolls in engagement with each other, a threaded post connected to said spring 95 means, a split nut engaging the threads on said post, toggles connected to the parts of said nut, and lever means pivoted on said post for breaking said toggles.

7. In a wringer having a frame, rolls and 100 spring means for yieldingly holding the rolls in engagement with each other, a threaded post connected to said spring means, a split nut engaging the threads on said post, toggles each having an arm which 105 carries a nut part, said toggles when straight holding the nut parts in engagement with the threads on said post, and lever means the ends of which project at spaced points from the wringer frame for 110 breaking said toggles.

8. In a wringer having a frame, rolls and spring means for yieldingly holding the rolls in engagement with each other, a threaded post connected to said spring 115 means, a split nut engaging the threads on said post, toggles each having an arm which carries a nut part, said toggles when straight holding the nut parts in engagement with the threads on said post, and a lever means 120 connected to said toggles and projecting at its ends from opposite sides of the wringer frame for breaking said toggles when the lever means is turned.

9. In a wringer having a frame, rolls and 125 spring means for yieldingly holding the rolls in engagement with each other, a threaded post connected to said spring means, two toggles each comprising a pair of arms pivoted together and having one 130

end pivoted to the frame, the other end carrying a nut part which when the toggle is straight engages the threads on said post, and means for breaking said toggles comprising means which form extensions of one of said toggle arms, one of said extension arms being connected to an arm of the other toggle.

10. In a wringer, a frame, rolls, a threaded post for increasing and decreasing the tension on the rolls, a nut part which normally engages the threads on said post, a toggle having an arm which carries said nut part, said toggle when straight holding the nut 15 part in engagement with the threads on said post, and means for breaking the toggle to move the nut part for engagement with the post.

11. The combination with a wringer comprising a frame, rolls, tension means for the rolls, and a screw which passes freely through the wringer frame and is guided thereby for increasing and decreasing the pressure exerted by the means on the rolls, 25 of a divided nut, the parts of which are movable toward and away from the screw from opposite sides, means for locking the parts of the nut in engagement with the screw, and manually operated means located 30 at different parts of the wringer frame, each of which when operated releases the parts of the nut and effects their simultaneous movement away from the post.

12. The combination with a wringer comprising a frame, rolls, tension means for the rolls, and a screw for increasing and de-

creasing the pressure exerted by the means on the rolls, of a divided nut for the screw, the parts of which are individually movable, a swinging means through which the screw 40 passes freely for moving the parts of the nut with respect to the screw, and means for moving the swinging means from either of its ends when it is desired to open the nut and permit the screw to move unrestrained.

13. The combination with a wringer, comprising a frame, rolls, tension means for the rolls, and a screw for increasing and decreasing the pressure exerted by the means 50 on the rolls, of a divided nut for the screw, the parts of which are individually movable, and a single lever which when moved in one direction moves the parts of the nut and holds them in operative engagement with 55 the screw and when moved in the opposite direction opens the parts of the nut and releases the screw and tension means.

14. The combination with a wringer comprising a frame having top and side members, said top member being U-shaped in cross section, and tension means, of a screw which passes freely down through the upper wall of the top member, a divided nut which embraces the screw below the top wall and 60 reacts thereon, and means operable from outside the frame for simultaneously moving the parts of the nut into and out of engagement with the screw.

In witness whereof, I have hereunto set my hand this 13th day of May, 1920.

GEORGE E. RANDLE.
